(57) **CLAIM**

The ornamental design for an anti friction part of a tongue buckle head of a safety belt as shown and described.

DESCRIPTION

FIG. 1 is a top, front, and right perspective view of an anti friction part of a tongue buckle head of a safety belt showing my new design;

FIG. 2 is a top, rear, and left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings depict structural seams of the anti friction part of the tongue buckle head of the safety belt that form no part of the claim design.

1 Claim, 8 Drawing Sheets
